LÉON BEAULIEU, OF LIMOGES, FRANCE.

MACHINE FOR CARROTING SKINS.

986,126.

Specification of Letters Patent. Patented Mar. 7, 1911.

Application filed November 22, 1909. Serial No. 528,367.

To all whom it may concern:

Be it known that I, LÉON BEAULIEU, of 29 Rue Auzette, Limoges, Haute-Vienne, Republic of France, manufacturer, have invented a Machine for Carrotting Skins, of which the following is a full, clear, and exact description.

The present invention has for its object to furnish a machine capable of effecting, 10 mechanically, the operation of carrotting skins, that is to say the operation of damping the hair of the skins with nitrate of mercury; the machine being equally adapted for use in dyeing all kinds of furs.

15 This machine, which permits a perfect and complete damping of the hair without wetting the leather and without diminishing the value of the leather of the skin, comprises a rotary brush provided with means 20 for distributing over its surface the exact necessary quantity of nitrate and adapted to impregnate therewith the hair of the skin which passes beneath the brush, the skin being suitably fed forward by driving 25 rollers.

One of the main features of the invention consists in providing the driving rollers with deep grooves.

30 Grooved rollers have already been employed for the purpose of feeding forward the skins, but the grooves were only superficial and their sole purpose was to propel the skins. According to the present invention, however, the teeth of one roller engage 35 deeply between the teeth of the coating roller, and moreover the teeth of the upper roller, which contacts with the hairy side of the skin, have roughened or serrated surfaces, so that that passage of the skin between the rollers tends to erect the hair and 40 prepare the skin for the brushing operation.

The machine comprises two pairs of feed rollers and two brushes arranged behind these rollers. The first brush receives the 45 liquid and makes it enter in the skin the hair of which have been erected by the first pair of rollers. The second pair of rollers again erects the hair and then the second brush completes the action of the first brush 50 and smoothes the hair.

The table of the machine, over which the

skin slides, is provided with a special arrangement so as to give to the skin a certain curve during the passage of the same between the rollers and under the brushes, 55 in order to obtain the most efficient action of the rollers and brushes. Moreover, the lower part of the table, is provided with longitudinal grooves or ridges having acute edges so that, should there be any excess 60 of liquid, the latter will lodge at the bottom of the grooves and the reverse side of the skin will not become wetted.

In the accompanying drawings which illustrate an example of the invention, 65 Figure 1 shows a side elevation of the machine, parts being shown in longitudinal section for the sake of clearness. Fig. 2 is a transverse sectional view of the table *a* taken on line A—A of Fig. 1. Fig. 3 is 70 an enlarged sectional view of a portion of the intermeshing feed rollers.

As will be seen on reference to the drawings, the machine comprises a table *a* provided with elements *a*¹, *a*², *a*³ of the shape 75 illustrated. The part *a* is made of glass and presents longitudinal grooves, ridges, or ribs as shown in Fig. 2. Preferably the ridges separating the grooves are very narrow so as to present a minimum area of surface for 80 contact with the skin. The table is slightly inclined from left to right (Fig. 1).

The machine is provided with two pairs of feed rollers *b* and *c* which are grooved and which mesh together as has been previously said, the grooves of these rollers are 85 deep, the teeth formed on the top roller being provided, as shown in Fig. 3 (which shows in section the teeth meshing together) with ridges or serrations *d*.

Between the rollers *b* and *c* is mounted a 90 rotary brush *e* above which is placed a distributing nozzle *f* connected by conduits *g* with a nitrate reservoir not shown. Behind the rollers *c* is mounted another brush *k*.

The rollers *b*, *c*, and the brushes *e* *k* are actuated by belts driven by pulleys fast on the driving shaft *l*. Flaps *m* afford access to the interior of the machine.

A grooved table *n* serves to collect the 100 excess of liquid, if any.

The operation is as follows: The skin is

presented to the two feed rollers *b* which, at the same time as they draw in the skin and feed it toward the brush *e*, raise the hair and prepare the skin for the action of the brush. It will be understood that, the skin being drawn in the direction of the arrows 1, the hair will be forced against the ridges *d* and so raised. The brush *e* is constantly damped by the exact required quantity of liquid. This liquid, consisting of a solution of nitrate of mercury, is distributed all over the brush by the nozzle *f*. Tap or other regulation devices enable the exact regulation of the quantity of liquid delivered to the brush. The brush *e* brushes the skin in the direction of the fur and impregnates the hair with nitrate. The brush *e* impregnates the hair with the required quantity of liquid and no more. The skin then passes between the two rollers *c* which raise the hair and continue the operation begun by the first rollers and by the brush *e*, permitting of the skin being fed forward without the leather becoming wetted, which would take place if the rollers were smooth or only provided with superficial grooves. The skin is then subjected to the action of the brush *k* which smoothes the hair and causes the liquid to penetrate to the roots; this brush at the end of a certain time of operation is slightly impregnated with nitrate. If certain portions of the hair which pass under this brush have received an insufficient quantity of nitrate from the brush *e*, the brush *k* gives up a small quantity of nitrate and completes the wetting. If on the contrary, the hair has received at certain portions an excess of nitrate, the brush *k* removes such excess, from which it will be seen that the brush *k* regulates the impregnating of the hair with nitrate.

The brush *k* acts as a regulator for insuring the uniformity of the work done.

As the parts *a*¹ and *a*² are respectively slightly below the lines of contact of the rollers *b* and *c* and that the element *a*³ has a curved shape as illustrated, it results therefrom that the skin *r* follows the path indicated in broken lines. The skin is not flatwise but curved, its concavity being toward the bottom when it passes between the rollers and toward the top when the said skin comes under the brushes.

Owing to the construction and arrangement of the various parts of the machine and to the mode of operation, the hair is thoroughly damped right down to the roots, whereas the leather of the skin is not wet. On the other hand, the employment of the table, ridged as described, prevents the inside of the skin becoming wetted in the event of the liquid flowing too quickly or unevenly. The

employment of a ribbed surface for the table has, moreover, the advantage of facilitating the sliding of the skin over the table. 65

The new machine, in addition to turning out perfect work which is more regular than that performed by hand, can be driven at a considerable speed.

The machine has also the advantage of 70 requiring a smaller quantity of liquid than is usually necessary for carrying out the work.

The different roller and brush arbors are 75 mounted in adjustable spring bearings.

The arrangements described are only given by way of example, as the shapes, dimensions and arrangements of details may be varied in all cases without departing 80 from the principle of the invention.

Claims:

1. In a machine for carroting and dyeing skins, co-acting feed rollers provided with teeth, said teeth being spaced from one another by deep grooves, the teeth of each 85 roller engaging the grooves of the other roller for erecting the hair.

2. In a machine for carroting and dyeing skins, co-acting feed rollers provided with teeth, said teeth being spaced from one another by grooves, the teeth of each roller engaging the grooves of the other roller, the teeth of one roller being provided with serrations for assisting in erecting the hair. 90

3. In a machine for carroting and dyeing skins two pairs of co-acting feed rollers provided with teeth spaced from one another by deep grooves, the teeth of each roller engaging the grooves of the other roller, and two rotary brushes, one of said brushes being arranged behind one of said pairs of rollers and the other of said brushes being arranged behind the other of said pairs of rollers. 95

4. In a machine for carroting and dyeing skins two pairs of co-acting feed rollers provided with teeth spaced from one another by deep grooves the teeth of each roller engaging with the grooves of the other roller, two rotary brushes, one of said brushes being arranged behind one of said pairs of rollers and the other of said brushes being arranged behind the other of said pairs of rollers, and means for feeding a fluid to one 100 of said brushes. 110

5. In a machine for carroting and dyeing skins, two pairs of co-acting feed rollers provided with teeth, said teeth being spaced from one another by deep grooves, the teeth of each roller engaging the grooves of the other roller, two rotary brushes, one of said brushes being arranged behind one of said pairs of rollers and the other of said brushes being arranged behind the other of said 115 120

pairs of rollers, and a table associated with said rollers and brushes, the portions of the table positioned in front of the rollers being straight and the portion of the table positioned adjacent one of said brushes being curved.

The foregoing specification of my ma-

chine for carrioting skins, signed by me this twelfth day of November 1909.

LÉON BEAULIEU.
